UNITED STATES PATENT OFFICE.

RUFUS N. CHAMBERLAIN, OF DEPEW, NEW YORK, ASSIGNOR TO GOULD STORAGE BATTERY COMPANY, OF DEPEW, NEW YORK.

STORAGE BATTERY.

No. 904,115.

Specification of Letters Patent.

Patented Nov. 17, 1906.

Application filed February 6, 1906. Serial No. 299,769.

To all whom it may concern:

Be it known that I, RUFUS N. CHAMBERLAIN, a citizen of the United States, residing at Depew, in the county of Erie and State of New York, have invented a new and useful Improvement in Storage Batteries, of which the following is a specification.

This invention relates to that class of battery receptacles, jars or tanks which comprise a wooden vessel, preferably lined with lead, and a cover having openings through which the terminals of the plates extend.

The object of my invention is to improve the parts by which the tank is closed at the top, with a view of rendering the apparatus more serviceable, durable and reliable.

In the accompanying drawings: Figure 1 is a sectional elevation of a battery receptacle or tank provided with my improvements. Fig. 2 is a top plan view thereof with the cover partly removed. Fig. 3 is a fragmentary vertical section through the cover and the upper part of the tank at right angles to Fig. 1, in line 3—3, Fig. 2. Fig. 4 is a fragmentary vertical section through the cover and upper part of the tank lining, in line 4—4, Fig. 2, on an enlarged scale.

Like letters of reference refer to like parts in the several figures.

A represents the outer portion of a four-sided battery tank or vessel, preferably of wood and provided with supporting rollers *a* and spacing side pieces *a'* of porcelain or other non-conducting material, two of these tanks A A being preferably secured together side by side in a well known manner.

B represents the inner portion or lining of the tank which is preferably constructed of antimonial sheet lead and secured in the outer or wooden portion by a layer of cement *b* in the usual way. This lining is provided above the outer portion with a top flange C comprising an outwardly-extending bottom portion or horizontal shoulder *c* and an upwardly-extending marginal portion *c'* having at its upper end an inwardly overhanging lip *c''*. The horizontal shoulder *c* supports the cover D which rests with its marginal portion *d* on this shoulder. The lip *c''* extends inwardly only over the outer portion of the horizontal shoulder *c*, leaving the inner portion of the shoulder exposed, and the cover D does not extend outwardly to the upright portion *c'*. This permits a solid or undivided cover to be placed upon the

shoulder *c*. The cover is provided inside of its marginal portion or flange *d* with an upright shoulder *d'*, formed preferably by arranging the marginal portion *d* of the cover at a lower level than the body portion 60 of the cover. The channel or groove which is formed above the horizontal shoulder *c* of the lining and the horizontal marginal flange *d* of the cover, and which is bounded on the outside by the upright portion *c'* of 65 the lining and on the inside by the upright shoulder *d'* of the cover, is filled with a cement packing E which is applied in a plastic condition and hardens and secures the cover securely in place. The inwardly overhanging lip *c''* of the lining prevents this packing from being raised out of its seat by the shocks to which the receptacle may be subjected when used on vehicles. Any suitable asphalt or petroleum composition or 70 cement may be used for this packing.

The cover, which may be made of any suitable material, for instance, hard rubber or antimonial lead, is provided with upright collars or short tubes F, through which the 80 terminals G of the plates G' extend upwardly. These collars or tubes preferably taper upwardly and are considerably larger in diameter than the terminals. The space 85 between these collars or tubes and the terminals is filled by bushings or packing sleeves H of yielding, non-conducting material which hold the terminals yieldingly in position and close the openings so tightly that the electrolyte is not liable to spatter or leak 90 through the same. These bushings are preferably made of sponge rubber which is so vulcanized as to have a smooth finish on the inner and outer sides, as indicated at *h h'*, to fit closely against the terminals and collars. 95 These soft and impervious bushings are so thick as to allow of considerable lateral movement of the terminal in the opening of the cover under the jarring which the battery is liable to receive when used on a rail- 100 way car or other vehicle, and this capacity of yielding in a lateral direction is greater than the possible lateral play of the plates in the vessel and prevents the jars or shocks from being transmitted to the cover and the 105 cement packing and injuring or destroying the same.

The cover is provided with the usual vent opening *i* closed by a stopper I.

The parts by which the jar or tank is 110

closed at the top are not corrodible to any considerable extent and remain in good working condition for a long time under the usual conditions of use, thereby maintaining a practically acid-tight closure for a long time and preventing leakage or spilling of the acid.

I claim as my invention:

1. The combination of a battery vessel having a top flange comprising a horizontal shoulder extending outwardly from the upper portion of the body of the vessel, an upright portion extending from the outer portion of said shoulder upwardly, and a lip 10 extending from the top of the upright portion inwardly over the outer portion of said shoulder, leaving the inner portion of said shoulder exposed, a solid cover resting flatwise with its marginal portion on said horizontal shoulder, a cement packing arranged between the edge of the cover and the upright portion and below the lip of said top flange, and terminals extending through said cover, substantially as set forth.
2. The combination of a battery vessel having a top flange comprising a horizontal shoulder extending outwardly from the upper portion of the body of the vessel, an upright portion extending from the outer portion of said shoulder upwardly, and a lip 15 extending from the top of the upright portion inwardly over the outer portion of said shoulder, leaving the inner portion of said shoulder exposed, a solid cover resting with 20 its marginal portion on said horizontal shoulder and having an upright shoulder ar-

ranged inside of said marginal portion and forming with said upright portion of the top flange a channel which is overhung by said lip, a cement packing arranged in said channel below said lip, and terminals extending through the cover, substantially as set forth.

3. The combination of a battery vessel having a top flange comprising a horizontal shoulder extending outwardly from the upper portion of the body of the vessel, an upright portion extending from the outer portion of said shoulder upwardly, and a lip 40 extending from the top of said upright portion inwardly, a cover provided with a marginal portion resting on said lateral shoulder and an upright shoulder arranged inside of said marginal portion and forming with said upright portion of the top flange a 45 channel of which the marginal portion of the cover and the horizontal shoulder of the top flange form the bottom, the upright portion of the top flange the outer wall and the upright shoulder of the cover the inner wall 50 and which channel is overhung by the lip on the top flange, a cement packing applied in said channel, terminals extending through openings in the cover, and bushings of soft rubber arranged in said openings around the 55 terminals, substantially as set forth.

Witness my hand, this 31st day of January, 1906.

RUFUS N. CHAMBERLAIN.
